MOTORCYCLE SHIELD

H. Dwight Anderson and David L. Travis, both of 2624
W. River Road, Minneapolis, Minn. 55406

Filed July 13, 1973, Ser. No. 379,117

Term of patent 14 years

Int. Cl. D12—11

U.S. Cl. D12—182

FIG. 1

FIG. 2

FIG. 4

FIG. 6

FIG. 5

FIG. 1 is a right side elevational view of a motorcycle shield embodying our new design the left side being a mirror image thereof;

FIG. 2 is a top plan view thereof;

FIG. 3 is a front elevational view thereof;

FIG. 4 is a rear elevational view thereof;

FIG. 5 is a front elevational view of a motorcycle shield showing a second embodiment of our new design; and

FIG. 6 is a sectional view taken along the line 6—6 in FIG. 5.

We claim:

The ornamental design for a motorcycle shield, substantially as shown and described.
